UNITED STATES PATENT OFFICE.

HAYWARD AUGUSTUS HARVEY, OF ORANGE, NEW JERSEY.

ROLLED-HEADED WOOD-SCREW AND PROCESS OF MAKING THE SAME.

SPECIFICATION forming part of Letters Patent No. 377,453, dated February 7, 1888.

Application filed September 19, 1887. Serial No. 250,125. (No model.)

To all whom it may concern:

Be it known that I, HAYWARD AUGUSTUS HARVEY, of Orange, New Jersey, have invented certain Improvements in Rolling-Dies for Finishing and Shaping the Heads of Wood-Screws, of which the following is a specification.

The objects of this improvement are to do away with the operation of shaving the heads of the ordinary flat-headed wood-screws, and to give to such heads the advantageous qualities which they acquire by being rolled. The effect of rolling is to so condense and stiffen the metal of which the heads are composed that they are given greatly-increased capacity of resisting any tendency to split along the line of the nick when the screw is being driven or forced into the object into which it is intended to be inserted.

20 The invention consists in finishing and shaping the head of a headed wood-screw blank by rolling such head between dies, each of which is provided with a ratchet-shaped groove, the walls of which groove are intended to bear, respectively, upon the top and upon the under side of the head of the blank, the wall intended to bear upon the top being less nearly perpendicular to the axial line of the blank than the top of the head of the blank is, and the wall 25 intended to bear upon the under side being more nearly perpendicular to the axial line of the blank than the under side of the blank is.

30 The accompanying drawings illustrate a form of dies which are included in the present invention, and which are adapted for rolling the heads of ordinary flat-head screws.

The drawings are as follows: Figure 1 is an axial section of the head and adjoining portion of the body of a flat-headed screw-blank and a transverse section of a pair of dies for rolling such head, showing the dies in the relative positions which they occupy at the instant of their first engagement with the head—that is, at the commencement of the rolling operation. Fig. 2 is a drawing similar to Fig. 1, except that it represents a later stage in the rolling operation. Fig. 3 is a drawing similar to Figs. 1 and 2, but representing the concluding stage in the rolling operation.

35 For clearness of illustration the drawings are purposely made on a magnified scale.

The dies A a may in the direction of the length be either straight or curved, and may be moved relatively in opposite directions; or one die may be held stationary while the other 55 is moved to perform the rolling operation, during the performance of which the space between the working-faces of the dies is appropriately lessened.

It is unnecessary to herein show mechanism 60 for operating the dies, because such mechanisms are well known, having been fully shown and described in Letters Patent of the United States, Nos. 223,730 and 357,001, dated, respectively, January 20, 1880, and February 1, 65 1887, granted to H. A. Harvey for improvements in machines for rolling the threads of wood-screws.

The characteristic feature of the dies A a is the shape in cross-section of the longitudinal 70 grooves A' a', with which they are respectively provided. It will be seen, upon comparing these grooves with the shape in axial section of the head B of the headed blank shown in Fig. 1, that the walls A² a² of the 75 grooves, respectively, which bear upon the top b of the head are so inclined as to make slightly obtuse angles with the parallel faces of the dies, and are hence inclined toward the head from a line perpendicular to the axial 80 line of the screw-blank. It will also be seen that the opposite walls, A³ a³, of the grooves, respectively, are less inclined from a line perpendicular to the axial line of the blank than the under side of the head is. It results from 85 this contour of the grooves in cross-section that when the dies first engage the head they bear upon the outer edge of the top of the head and upon a point near the body upon the under side of the head. As the rolling operation proceeds, the outer portion of the head is bent toward the body of the blank, as illustrated in an extravagant way in Fig. 2. When the operation of rolling is concluded, the head is so far set back that it completely fills the 90 95 grooves, as illustrated in Fig. 3, in which, as will be seen, the top of the head is very slightly conical or full in the center.

It will of course be perceived that the top of the head when finished will have acquired 100 the shape in reverse of the walls A² a² of the grooves, and that the top of the head when

finished can be made either more or less conical or more or less spheroidal by suitably varying the contour in cross-section of the walls A^2 a^2 of the grooves.

5 The grooves A' a' , adapted to bear initially upon the exterior portion of the top of the head and upon a part of the under side of the head near the body, are especially suitable for rolling the heads of ordinary flat-headed screws. Doubtless other forms of grooves may be usefully employed for the same purpose; but grooves having the characteristics and mode of operation shown and described are preferred, and have proved peculiarly effective for the desired purpose.

15 The head, usually after having been rolled, is nicked in the ordinary manner, and it will be found that the condensation to which the metal composing the head has been subjected during the rolling operation has greatly stiffened it and increased the ability of the head to resist strains tending to split it along the line of the nick.

20 Screw-blanks which have been headed in solid dies in the ordinary double-blow header may have their heads perfectly finished by the herein-described process of rolling, so that the ordinary process of shaving the heads can be dispensed with. It will of course be seen that

the heads of shaved blanks may also be rolled, 30 as herein described, and will thereby be rendered more capable of resisting strains tending to split them, as herein set forth.

What is claimed as the invention is—

1. As a new article of manufacture, a wood-screw provided with a rolled head the top of which is slightly conical or conoidal, substantially as described. 35

2. For employment in rolling the heads of flat-headed blanks or screws, finishing and 40 shaping dies, each of which is provided with a ratchet-shaped groove, one wall of which groove is less nearly perpendicular to the axial line of the blank than is the top of the headed blank upon which it is intended to bear, 45 and the other wall of which is more nearly perpendicular to the axial line of the blank than the under side of the head of the blank upon which it is intended to bear, whereby the initial bearing-points of the dies upon the head 50 upon which they act are respectively upon the outer portions of the top of the head and upon portions of the under side of the head near the body, substantially as set forth.

HAYWARD AUGUSTUS HARVEY.
